UNITED STATES PATENT OFFICE.

WILLIAM H. WHITCOMB, OF NEWTON, MASSACHUSETTS.

SHARPENING DEVICE FOR KNIVES AND THE LIKE.

1,173,627.

Specification of Letters Patent. Patented Feb. 29, 1916.

Application filed November 13, 1914. Serial No. 872,028.

To all whom it may concern:

Be it known that I, WILLIAM H. WHITCOMB, a citizen of the United States, residing at Newton, in the county of Middlesex and 5 State of Massachusetts, have invented new and useful Improvements in Sharpening Devices for Knives and the like, of which the following is a specification.

This invention relates to new and useful 10 improvements in sharpening devices for knives and the like.

The object of the invention is to provide a simple, durable sharpening device for knives, said device having coöperating 15 sharpening members arranged substantially parallel to each other, but capable of being moved while in such parallel relation toward and from each other. Furthermore, if desired, said members may be adjusted at 20 the will of the operator to occupy varying angular positions relatively to each other in order to facilitate the sharpening of knives having blades differing in thickness and in 25 the inclination of the bevels which form their cutting edges.

The invention consists in the combination and arrangement of parts set forth in the following specification and particularly pointed out in the claims.

30 Referring to the drawings: Figure 1 is a plan view of a device embodying the preferred form of my invention. Fig. 2 is a side elevation of the same illustrating in dotted lines other positions which the parts 35 of the device may occupy. Fig. 3 is a transverse section of one of the fingers of the device, said section being taken on the line 3—3 of Fig. 1. Fig. 4 is a plan view of a modified form of knife sharpener. Fig. 5 is a section 40 taken on line 5—5 of Fig. 4. Fig. 6 is a side elevation of still another modification of my invention.

Like numerals refer to like parts throughout the several views of the drawings.

45 In the drawings, 8 and 9 represent a pair of parallelly disposed coöperating members, each of said members preferably consisting of a set of fingers 10, said sets of fingers being arranged in staggered relation relatively 50 to each other, that is to say, the fingers of the member 9 are provided with intervening

spaces 11 through which the fingers of the member 8 are adapted to be moved, while the member 8 is likewise provided with spaces 12 for receiving the fingers of the member 9. 55

The members 8 and 9 are connected together by a resilient sinuously formed member 13 constituting a spring, said spring being arranged at one end of said members 60 and permitting said members either to be moved in parallel relation by the compression or extension of said spring toward and from each other, or said spring is adapted to permit said members 8 and 9 to occupy varying angular positions relatively to each other. Said spring serves as a pivot for said members when the same are moved to occupy the last mentioned positions. 65

The members 8 and 9 are preferably constructed of sheet metal and formed integral with the spring 13. The inner adjacent faces of said members 8 and 9 are roughened whereby a knife inserted between said faces, as indicated at "A" Figs. 1 and 2, and reciprocated transversely of the fingers 10 70 will be ground off and sharpened. 75

To best accomplish the roughening of the inner faces of the members 8 and 9 said members are provided with longitudinally 80 disposed dovetailed grooves 15 formed by turning inwardly portions of the sheet metal constituting the members 8 and 9 to form the intervening spaces 11 and 12, and into the grooves 15 are inserted sections of 85 sharpening material 16, said sections being beveled at the sides to fit the dovetailed grooves 15. The outer surfaces 17 of the members 8 and 9 are also roughened preferably by means of longitudinal corruga- 90 tions 18, see Figs. 1 and 3.

Figs. 4 and 5 illustrate a modified form of sharpener in which form parallelly disposed members 19 and 20 are provided having fingers 21 similar to the fingers 10, as shown 95 in Fig. 1, said members 19 and 20 being connected by a resilient member or spring 22 which instead of being integral with the members 19 and 20 is formed of sheet metal and attached to said members, which are 100 preferably formed of wood. The ends of the spring 22 are formed into pockets 23 which

receive the ends of the members 19 and 20, while spurs 24 are formed by partially detaching portions of the metal constituting said spring which spurs are driven into the wood wherever desired, preferably at the end of said members 19 and 20 and secure said spring thereto. The adjacent faces 25, 26 and the outer faces 26 of the members 19 and 20 may be roughened preferably by 10 securing thereto an abrasive substance, such as emery.

In Fig. 6 still another form of device is illustrated. In this form the parallelly disposed members 19 and 20 are preferably 15 identical in form and construction with those illustrated in Figs. 4 and 5, but in this form said members are connected together by springs 27 and 28, preferably formed of wire, with spurs 29 at suitable points and 20 preferably constructed of the same material which constitutes securing means to be driven into the wood constituting the members 19 and 20. Said springs are bent intermediate their ends into coils 31 to permit 25 said parallel members to be moved toward and away from each other.

To operate the devices hereinbefore specifically described the operator holds the sharpener at points "B" and "C" and inserts a knife "A," as illustrated in Figs. 1 and 2. Pressure is then applied at the points "B" and "C" causing the members 8 and 9 to be moved toward each other to yieldingly engage opposite sides of the blade adjacent the cutting edge. The knife is then reciprocated transversely of the fingers 10 until the knife has been sharpened sufficiently. To vary the angle of the bevels forming the cutting edge of said knife, the 40 members 8 and 9 may be moved to occupy different angular positions relatively to each other, or in other words, cause the plane containing the faces 14 to intersect each other at different distances from the ends of 45 said members 8 and 9. The surfaces 14 may be rougher, if desired, than the surfaces 17 or vice versa and after the knife "A" has been reciprocated between the surfaces 14, the members 8 and 9 may be moved to occupy 50 the position shown in dotted lines Fig. 2, and the knife placed, as shown at "D" and reciprocated as before, whereupon a finer and smoother cutting edge may be secured.

55 Having thus described my invention what I claim and desire by Letters Patent to secure is:

1. A knife sharpener comprising coöperating sharpening members, the adjacent faces 60 of said members being roughened, and resilient means arranged to connect said members together and adapted to permit said members to be moved in parallel relation toward and from each other.

2. A knife sharpener comprising coöperating sharpening members, and means connecting said members together adapted to permit the connected portions of said members to be moved toward and from each other, said means also being adapted to permit a 70 pivotal movement between said members.

3. A knife sharpener comprising a plurality of sets of parallelly disposed members having roughened adjacent surfaces, resilient means connecting said sets of members 75 together and adapted to permit said sets to be yieldingly moved toward and from each other, said resilient means also being adapted to permit said sets to occupy varying angular positions relatively to each other. 80

4. A knife sharpener comprising parallelly disposed members, a sinuously formed spring interposed between and connecting said members together, and sections of sharpening material secured to the adjacent faces 85 of said parallel members.

5. A knife sharpener comprising parallelly disposed members formed from sheet metal, a sinuously formed spring integral with and connecting said members together 90 and adapted to permit said members to be yieldingly moved in parallel relation toward and from each other, said spring also permitting said members to occupy varying angular positions relatively to each other, and 95 means on said members adapted to sharpen a knife.

6. A knife sharpener comprising two parallelly disposed sets of members, the members of one of said sets being arranged in 100 staggered relation to those of the other set, resilient connecting means for said sets adapted to permit said sets to be moved in parallel relation toward and from each other and to occupy varying angular positions 105 relatively to each other, the adjacent and outermost faces of the members of said sets being roughened and adapted to sharpen a knife.

7. A knife sharpener comprising a pair of 110 parallelly disposed sets of fingers constructed of sheet metal and bent to form dovetailed grooves, the fingers in one of said sets being arranged in staggered relation to those of the other, sections of sharpening material 115 adapted to fit said dovetailed grooves, and resilient means interposed between and connecting said sets.

8. A knife sharpener comprising a pair of parallelly disposed sets of fingers, the 120 fingers in one of said sets being arranged in staggered relation to those of the other set, the adjacent and outer portions of said fingers having roughened faces adapted to sharpen a knife, and means integral with 125 both of said sets of fingers constructed and arranged to permit the fingers of said sets to be moved in parallel relation toward and

from each other or to occupy varying angular positions with the fingers of one of said sets passing through intervening spaces in the other of said sets, whereby a knife may be yieldingly held in contact with either the adjacent faces of said sets or the outer faces thereof.

Copies of this patent may be obtained for five cents each, by addressing the "Commissioner of Patents, Washington, D. C."

In testimony whereof I have hereunto set my hand in presence of two subscribing witnesses.

WILLIAM H. WHITCOMB.
